ANNIBALE A. GUERINI, OF MIDDLEBORO, MASSACHUSETTS.

FIREPROOF BUILDING.

1,189,360.

Specification of Letters Patent.

Patented July 4, 1916.

Application filed February 8, 1909. Serial No. 476,609.

To all whom it may concern:

Be it known that I, ANNIBALE A. GUERINI, of Middleboro, in the county of Plymouth and State of Massachusetts, have invented 5 certain new and useful Improvements in Fireproof Buildings, of which the following is a specification.

The object of this invention is to make possible the construction of a building of reinforced concrete without requiring the 10 building as a whole to be cast in a mold. In other words, it is my object to simplify and cheapen the construction of fire-proof buildings by constructing the several members 15 and parts of the buildings independently out of concrete, of which all the long members are reinforced with metal, so that a building of any size or design may be constructed without requiring special molds to 20 be prepared therefor, which buildings, when completed, will have the appearance of an artistically finished stone or plaster building without the unsightly mark made by the 25 ordinary wooden models used when the walls of a building are cast in place.

In carrying my invention into effect I provide for the construction of beams, studs, joists, rafters and other framing members independently of one another, of reinforced 30 concrete cast in any sort of mold that may be convenient, and in any convenient place before being assembled. The floor joists and rafters made in this manner are constructed with lateral brackets or abutments serving 35 as temporary supports for the diagonal bracing or strutting. These diagonal braces between the joists are also made of concrete with or without reinforcing, and are cemented to the joists. The outer coverings 40 for the roof and wall are of concrete tiles hung to the rafters and wall studs in a manner which will be later described, and the floor is of concrete tiles laid across the joists, on which may be laid a wooden floor if desired. The members thus made are assembled 45 together in the same manner as are the parts of wooden buildings, to make a framed structure, and are suitably tied together, as will be presently described, and the joints between the several members protected and 50 made solid by the application of cement or mortar. Thus practically the entire building is made of fire-proof material. In order to permit fastening of a wooden floor and 55 other wooden fittings, the frame members are provided with inset nailing strips of

wood or equivalent material, which, however, are embedded in the concrete so as to be practically incombustible.

Of the accompanying drawings, Figure 1 60 represents a perspective view of a house built in accordance with my invention. Fig. 2 is a perspective view of the system of framing employed in such a building where the members are of reinforced concrete. 65 Fig. 3 represents a sectional view of one of the floors of a building constructed in accordance with my invention. Fig. 4 is a sectional view of one of the walls, showing part of the roof and floors of such a building. Fig. 5 is a perspective view of part of the 70 roof framing of the building. Fig. 6 is an elevation of a form of tile adapted to be used as part of the outer covering for the walls and roof. Fig. 7 is a sectional view, 75 on an enlarged scale, of part of the wall of the building, taken through the center of one of the upright studs. Fig. 8 is a similar view taken between two of the studs. Fig. 9 is a plan view, showing a type of tile somewhat different from that of Fig. 6. Figs. 10 80 and 11 are views similar to Figs. 7 and 8 respectively, showing the manner of attachment of the tile illustrated in Fig. 9. Fig. 12 is a perspective view of a strip adapted 85 for use in the suspension of roof and wall tiles.

The same reference characters indicate the same parts in all the figures.

For an explanation as to the manner in 90 which my invention is carried into effect reference may be had first to Fig. 2. In this figure, 1 represents one of the floor beams, girders or sills, which constitute the 95 main supporting members of the frame. 2 represents the upright studs or joists, and 3 the horizontal joists supporting the floor. Each of these members is made as an independent reinforced concrete beam, which is 100 cast separately and independently of the others and afterward assembled in the manner necessary to construct a complete building. Each of the girders or beams 1 has shelves or brackets 4 5 extending throughout its entire length, and a longitudinal 105 groove or mortise 6 in its upper surface or edge. The groove serves for the reception of tenons 7 which are cast in the ends of the upright studs. These tenons are preferably 110 bars or blocks of metal around which the concrete is cast. By reason of the fact that the groove 6 is continuous, the studs may be

set in any position on the beam, and their tenons will enter the groove. This enables standard beams to be made capable of being used for buildings of all sizes and styles of design. The beams which are used for the sills of the building, as they rest directly on the basement walls, have mortise grooves only in their upper surfaces, but the beams which support the upper floors and the roof are grooved in their under sides as well, as appears from Fig. 4. Furthermore, those beams which lie in the walls of the building, and which may be termed the wall beams or wall plates, have shelves only on their inner sides, instead of on both sides, as shown in Fig. 2.

The joists 3 are notched at their ends in the lower portions, as represented at 8, forming shoulders which rest upon the shelves 4. These joists have lateral openings or perforations 9 extending through them, and the beams 1 also have perforations 10 on each side of the points at which the ends of the joists are adapted to abut. In building up the frame the ends of the joists are set on the shelves 4 5 between the holes 10 of each pair thereof, and a tie or strap 11 is then passed through the holes 9 10 around the portions of the beam and joist included between them, and made fast. Any form of tie which gives the necessary amount of strength may be used. For instance, I may employ such a one as shown at 11^a in Fig. 4, where the tie member is a strap bent in U-form, and passed through the holes 9 and 10. Its ends are threaded and passed through holes in a bar 12, which lies along the outside of the beam or sill 1^a. Nuts 13 are screwed upon the ends of the strap and hold the bar 12 thereon. The tie members may also be wires passed through the holes and around the parts of the beams one or more times, and their ends suitably fastened together.

Projecting laterally from the floor joists near the bottom and top edges thereof, respectively, are abutments 14 15, the former of which I term brackets, and the latter arrests. These abutments are provided for holding the diagonal braces or struts 16 in place when they are first assembled. These diagonal braces are of concrete, are made of such a length as to fit snugly between the corresponding brackets and arrests of adjacent joists, and their ends are beveled to fit against the sides of the joists. After being put in place, they are secured by cement or plaster, which unites their ends immovably to the joists. Preferably the abutments 14 and 15 are made independent of one another at the points on the joists where the bracing is to be set, and they may also be made as continuous shelves or ribs if desired.

After the vertical studs and the joists are set in place on the beams, the mortise

grooves between the studs and the space above the shelves are filled with cement, as shown at 20 in Fig. 2, giving the beam a rectangular cross section and firmly embedding the tenons of the studs and the ends of the joists, as well as protecting the straps 11 against corrosion and injury by fire.

The roof in the form which I prefer to use is constructed of horizontal tie beams 21 laid across the uppermost beams of the wall, 75 and rafters 22. The ends of the tie beams have shoulders 23 against which the outer ends of the rafters abut, and by which they are prevented from slipping outward. The inner ends of the rafters abut against a longitudinal ridge beam 24 and against each other beneath said beam. They are united by tie straps 11^b with the tie beams, and by straps 11^c and 11^d with the ridge beams and with each other. The rafters as well as the 85 floor joists are provided with abutments 14 and 15 for diagonal bracing if desired. All the joints between the members of the frame are covered and bonded together with cement.

In order to further strengthen and stiffen the building, I provide diagonal tie members 25 and 26 at the corners of the building. The members 25 are united to the corner studs and to the wall beams which rest upon them, while the tie members 26 are carried diagonally between the beams and sills of upper and lower stories. These ties may be metal rods or equivalent fastenings, and are secured to ring bolts 27 cast into the studs 100 and ring bolts 28 in the beams, respectively. These tie members are provided between the sills of the building and the floor above, between each of the floors, and between the upper floor and the beams which support the 105 roof.

At the corners of the building, or at other points where two of the main beams come together, one of the beams is notched at the end at its under side, in the same manner 110 as are the joists, and the notched end is placed upon the shelf of the beam against which it abuts.

All of the main members of the frame have metal reinforcing as illustrated in Fig. 115 4, the reinforcing members or elements consisting of the longitudinal bars or rods 29 and inclined shear bars or rods 30. These reinforcing members may be made according to any system of concrete reinforcing, 120 but preferably according to some system which provides a truss. The one prime essential in the construction and arrangement of the reinforcing is that there shall be a reinforcing element in any part of the frame members which is surrounded by a tie. In other words, that the reinforcing elements shall lie between the perforations 9 10 respectively of the beams, and the nearest edge or end of the same. This is in order that the 130

weakening of the beams by the perforations and the stresses locally applied thereto through the tie straps shall not cause the beams to fracture.

- 5 The frame members have nailing strips 31 of wood or equivalent soft material suitable to receive nails, embedded longitudinally in them in the sides or edges thereof, which lie in any of the interior or exterior walls of 10 the building. In addition, those of the upright studs which are placed so as to flank a window or door opening have nailing strips 32 at their corners. These strips are placed in the molds in which the beams are 15 cast, so as to be embedded therein, and are securely anchored, as by having their embedded sides of greater width than the exposed sides, or by having hook-shaped or otherwise offset anchors 33 attached to them 20 and surrounded by the concrete. The transverse or horizontal beams which lie in the walls of the building have in addition vertical strips 34 embedded in their outer surfaces and extending transversely of their length. 25 Preferably also the nailing strips in the upper edges of the floor joists and beams, as shown in Fig. 3, project above the body of the beams, although it is not necessary that they should do so, but the other strips may 30 be, and preferably are, flush with the concrete body. The strips in the upper sides of the floor members are used for attaching a wooden floor, while the strips in the under sides of such beams and in the inner side of 35 the vertical studs are employed for the attachment of lathing 36 on which a coat of plaster 37 is spread.

A convenient form of floor construction is shown in Fig. 3. On the upper edges of 40 the joists are laid concrete slabs 38 between the nailing strips 31 of adjacent joists. Across the tiles are laid purlins or boards 39 and transversely of the latter are floor boards 40. The purlins 39 are nailed to the strips 45 31, and the boards 40 are nailed to the purlins. If desired, the wooden flooring may be dispensed with and the slabs 38 covered with a mosaic or tiled floor. In any event, however, the tiles give protection against fire 50 to the flooring so that it is impossible for a blaze in one apartment to be communicated to the apartment above.

The outer covering for the walls and roof is made of concrete tiles hung upon horizontal bands or lines stretched along the walls and roof. These lines or bands are fastened by nails 41 driven into the external nailing strips 31 of the wall studs. The wall covering is made of tiles 42 which 60 have lips or hooks 43 which are hung on the bands or ties so that the main body of the tile is suspended therefrom. Bands 44 consisting of wires, are illustrated in Figs. 1, 7 and 8. These wires are stretched 65 along the walls and held by the nails 41,

conveniently by having a turn of the wire taken around each nail. Instead of the wire, perforated metal strips or bands 45 (Fig. 12) may be employed, such bands having holes 43 spaced conveniently for the 70 reception of the fastening nails 41. The wires or strips have preferably a less distance between them than the length of the tiles, as shown in Figs. 7 and 8, so that the tiles overlap and form the appearance of a 75 shingled roof. The overlapping of this type of tile causes the tiles to slant outward so that they are held in place by gravity, and by the weight of tiles above. If desired, however, they may be additionally 80 secured by a tie of wire 47 passed through holes 48 in the tiles, and laid in grooves 49 extending from such holes to the upper edges of the tiles. These wire ties are fastened in any suitable manner, as by 85 twisting their ends together. The backs of the tiles are covered with cement, in which the hooks 43 and the supporting wires are embedded, and also the wire ties 47, when the same are used. Preferably the entire 90 space between the plane of the outer edges of the studs 2 and the tiles is filled with cement, which binds the tiles together, covers the joints between them, and makes a complete homogeneous, weather-tight 95 wall. The upper course of tiles is clamped down by a slab 50 which extends throughout the whole length of the wall, as shown in Figs. 1 and 4, and is clamped by bolts anchored in the upper horizontal wall beam. 100

Another type of tile is illustrated in Figs. 9, 10 and 11. This tile is made to simulate dressed stone, and is arranged to overlap a flange of the tiles next beneath and to one side thereof. The tiles are represented by 51 and the flanges thereof by 52. These tiles hang vertically from the wires or bands from which they are suspended, and have the perforations 53 for the reception of tie wires 54, which are here 105 necessary for their retention. In addition also, the laterally extending portion of the tile flange may be provided with perforations 55 for an additional intermediate tie 56. It may be noted that in Figs. 7 and 8 110 the supports for the tiles are wires, while in Figs. 10 and 11, the corresponding supports are the strips 45, shown in Fig. 12.

Preferably such strips are used for spacing the roof tiles 60. A convenient mode of 120 attachment of such strips is illustrated in Fig. 5, where the strips 45 are shown as nailed to blocks of wood or the like 61, which in turn are secured to the nailing strips 31 of the rafters. It is obvious, however, that the strip may be nailed directly to the wooden insert of the rafter, and that wires instead of the strips may be employed.

Preferably in laying the roof tiles, each course is covered with a layer of cement or 125

mortar, before the next tile course is superposed, thus guarding against the inflow of water, due to accumulation of snow or ice on the roof. The roof tiles, as well as the wall tiles, are provided with hooks or flanges which take over the strips or wires, by which the courses of tiles are spaced. In addition, the under surface of the tiles is coated with cement.

10 From the foregoing it will be seen that by my invention I have provided a new form of fire-proof building, which is constructed of absolutely fire-proof material, and can be built at any place and according 15 to any design by unskilled workmen who need only have knowledge enough to distinguish the identifying marks which may be applied to the various members. The several beams constituting the frame of the 20 building may be made at any point where facilities exist for the purpose, in accordance with the design of the building, and also in standard patterns adapted for any 25 design. They can then be shipped to the point where the building is to be erected, and easily assembled together.

I claim:—

1. In a fire-proof building, the combination with concrete fire-proof uprights made 30 as independent monoliths, each having a mailing strip set into its outer face, suspension bands strung horizontally across said uprights and from one upright to another and secured by nailing to said strips, tiles 35 having hook-like ledges projecting from their inner sides at their upper edges hung from said bands, said tiles being of greater length than the distance between the bands whereby the tiles above overlap the upper 40 portions of those beneath, and an incombustible covering for said mailing strips.

2. In a fire-proof building, the combination with concrete fire-proof uprights made 45 as independent monoliths, each having a mailing strip set into its outer face, suspension bands strung horizontally across said uprights and from one upright to another and secured by nailing to said strips, tiles 50 having hook-like ledges projecting from their inner sides at their upper edges hung from said bands, said tiles being of greater length than the distance between the bands whereby the tiles above overlap the upper 55 portions of those beneath, tying means pass-

ing through apertures in the upper portions of the tiles below such ledges and carried about the same and the suspension bands, whereby to lock the tiles in place, and a fire-proof protecting covering for said nailing strips.

3. In a fire-proof building, the combination with concrete fire-proof uprights made as independent monoliths, each having a mailing strip set into its outer face, suspension bands strung horizontally across said 60 uprights and from one upright to another and secured by nailing said strips, and tiles having hook-like ledges projecting from their inner sides at their upper edges hung from said bands, said tiles being of greater 65 length than the distance between the bands whereby the tiles above overlap the upper portions of those beneath, and a backing of cement overlying the entire rear faces of the 70 tiles in which the ledges are embedded.

4. In a fire-proof building a shell construction comprising uprights and rafters comprised of monolithic concrete columns and bars each having a strip of wood or equivalent mailing material inserted in its 80 outer face, suspension members extending transversely of said uprights and rafters, being secured by nails, screws, or the like, to said strips, and engaged with said suspension members, and concrete tiles having hook elements adapted to overlie and be engaged with said suspension members, each suspension member thereby sustaining a row of tiles, and an incombustible plastic filling interposed between said mailing strips 85 and the overlying tiles.

5. A fire-proof wall construction comprising monolithic uprights each having a wooden mailing strip embedded in one side, substantially horizontal bands extending 95 across said uprights, fastening means driven into the wooden mailing strips and engaged with said bands to secure the latter in place, tiles having hook-like projections suspended from said bands by engagement of such projections thereover, tie wires passing through the tiles and around said bands, and a back of fire-proof plastic material between the 100 tiles and uprights.
